US0D1053140S

(12) **United States Design Patent** (10) **Patent No.:** **US D1,053,140 S**
(45) **Date of Patent:** **** Dec. 3, 2024**

(54) **MULTIPOINT FOR OPTICAL CONNECTIONS**

(71) Applicant: **Corning Research & Development Corporation**, Corning, NY (US)

(72) Inventors: **Steven Mardis Bagley**, San Francisco, CA (US); **Robert Bruce Elkins, II**, Hickory, NC (US); **Scott M. Janis**, El Cerrito, CA (US); **Matthew Wallace Peterson**, San Francisco, CA (US); **Joel Christopher Rosson**, Hickory, NC (US); **Dayne Wilcox**, El Cerrito, CA (US)

(73) Assignee: **CORNING RESEARCH & DEVELOPMENT CORPORATION**, Corning, NY (US)

(**) Term: **15 Years**

(21) Appl. No.: **29/796,033**

(22) Filed: **Jun. 22, 2021**

CLAIM

The ornamental design for a multiport for optical connections as shown and described.

DESCRIPTION

FIG. 1 is a front perspective view of a multiport for optical connections showing our new design;

FIG. 2 is a top view thereof of FIG. 1;

FIG. 3 is a bottom view thereof of FIG. 1;

FIG. 4 is a right side view thereof of FIG. 1;

FIG. 5 is a left side view thereof of FIG. 1;

FIG. 6 is a front view thereof of FIG. 1; and,

FIG. 7 is a rear view thereof of FIG. 1.

In FIGS. 1-7, the evenly-spaced broken lines illustrate portions of the article that form no part of the claimed design.
